UNITED STATES PATENT OFFICE

HAROLD M. LEWIS, OF DOUGLASTON, NEW YORK, ASSIGNOR, BY MESNE ASSIGNMENTS, TO WIRED RADIO, INC., OF NEW YORK, N. Y., A CORPORATION OF DELAWARE

COMMUNICATION SYSTEM

Application filed June 15, 1927, Serial No. 199,092. Renewed August 1, 1931.

My invention relates broadly to electrical communication systems and more particularly to an alternating current signal transmission and reception system.

5 One of the objects of my invention is to provide a system of communication whereby transmission of signaling energy may be effected to a selected receiving station only when that receiving station is in condition 10 to receive the signaling energy.

Another object of my invention is to provide a cooperative system of intercommunication between transmission and receiving stations wherein both the transmission and 15 receiving stations cooperate to produce the signaling currents which may be modulated or modified at the transmitter for rendering the signals intelligible at the receiver.

Other and further objects of my invention 20 reside in the cooperative arrangement of circuits between transmission and receiving apparatus, as will be more fully understood from the specification hereinafter following by reference to the accompanying drawings 25 in which:

Fig. 1 is a theoretical diagram illustrating the principles of my invention applied to a line wire intercommunication system; Fig. 2 shows one of the practical applications of 30 my invention to a line wire telephone system; Fig. 3 illustrates a two-way intercommunication space radio system embodying the principles of my invention; and Fig. 4 shows the 35 cooperative transmitter and receiver circuits of my invention applied to a space radio channel in which a different signaling frequency is transmitted in each direction simultaneously for controlling the circuits at each terminal station.

40 Referring to the drawings in detail, in Fig. 1 reference character 1 designates one terminal station and reference character 2 designates a cooperating station connected by line wires Y and X. Terminal station 1 includes the electron tube 3 having its input 45 circuit connected to the line wire system Y and its output circuit completed through inductance 4 and high potential source 5. The cathode of tube 3 is heated from battery 6. 50 The high potential battery 5 is by-passed

by means of condenser 7 to permit the establishment of high frequency oscillations. The output circuits 4, 5, 7 are rendered ineffective for producing any voltage effect on the input circuit of tube 3 directly by reason 55 of the arrangement of the neutralizing circuit including the portion of inductance 8 and the condenser 9. I have indicated a shielding 10 preventing any magnetic influence between the output and input circuits of the tube 3. At station 2 the electron tube 11 is similarly arranged with its input circuit connected to line wire system X and its output circuit including portion of inductance 12 and high potential battery 14 60 shunted by by-pass condenser 15. The cathode of tube 11 is heated from battery 16. A neutralizing circuit including condenser 17 and portion of inductance 18 are arranged for preventing any direct influence of the 65 output circuit upon the input circuit of tube 11. Magnetic coupling between the input and output circuits is prevented by suitable shielding represented at 19. The output circuit of the tube 11 is connected to the line 70 wire system Y by means of inductance 20 which couples with inductance 12. The output circuit of electron tube 3 is connected to line wire system X by means of inductance 21 which couples with inductance 4. It will 75 be clear that by reason of isolation of the input and output circuits of the tubes at each terminal station neither tube can in itself be a generator of oscillations but cooperatively the system will generate oscillations of a 80 frequency depending upon the constants of the circuit. The interconnecting wires Y and X have been represented by dotted lines connecting the two intercommunication distance stations 1 and 2. By adjusting the feed back 85 to a degree sufficient to overcome the attenuation of the lines the circuit will oscillate at a common or carrier frequency. A modulating signal such as voice frequency current will affect the carrier at all parts of 90 the circuit so that a voice modulation at station 1 will be effective at station 2 and vice versa. The carrier frequency is cooperatively generated by the communicating stations. 95

In Fig. 2, I have illustrated one of the prac- 100

tical applications of my invention in a carrier current telephone system. The stations 1 and 2 are interconnected by a single pair of wires. A hybrid coil system is illustrated at 22 forming the connection of terminal station 1 to the line wire system. A balancing network BN is shown at each end of the line wire system. The electron tube 3 at terminal station 1 is shown arranged in an oscillator circuit with the input circuit thereof provided with a condenser 23 for predetermining the resonant or oscillating frequency. The output circuit is prevented from regenerating with respect to the input circuit.

15 The function of the hybrid coil is to provide a bridge form of balance (neutralization) between the output circuit of the electron tube and its own input, and at the same time allow incoming signals from the line to affect the input circuit and allow the output of the tube to be applied to the line. The impedance of the line is in one leg of the bridge and is balanced by BN in another leg. The input of the electron tube is therefore connected to points which are conjugate to the points across which the output voltage is applied. The output of station 1 is thus effective only upon the input of station 2 and the output of station 2 is only effective upon the input of station 1. I have illustrated a modulation circuit including microphone 24, source of potential 25, transformer system 26 and electron tube system 27 for controlling the operation of the oscillator system 1. A telephone receiving circuit has been represented at 28 including telephones 29.

At the terminal station 2 a hybrid coil system is represented at 30 with which the circuits of electron tube 31 are associated.

40 The input circuit of electron tube 31 is tuned by means of variable condenser 32 and connects across the line system as shown. Regeneration between the input and output circuits of electron tube 31 is prevented. A modulation system is provided for the oscillator 31 which comprises microphone 33, source of potential 34, transformer system 35 and electron tube 36. The output circuit of electron tube 36 is coupled with the oscillator system for controlling the operation thereof. A telephone receiver circuit is shown at 37 to which is connected the telephone receiver 38. Due to the rectifying action of the tubes the signal currents will be reproduced at both terminal stations 1 and 2. The two stations 1 and 2 are so connected that they cooperate to generate a carrier frequency determined by the constants of the circuit, and voice frequency modulating currents operate to produce the side bands or modulate the carrier wave.

In Fig. 3 I have illustrated the application of my invention to a space radio system where terminal stations 1 and 2 are provided with loop antennæ represented at 39, 40, 41

and 42. The input circuit of the tube 3 is connected with the loop system 39 with suitable tuning means represented at 23 in circuit therewith for adjusting the circuits at the terminal station 1 for the reception of incoming signals which are radiated from loop system 42 at terminal station 2. The output circuit of electron tube 3 includes a source of potential 5, the winding 43, the loop conductor 40 and the primary winding of 75 the telephone transformer 28 connected to the plate electrode of tube 3. The loop circuit 40 may be tuned by means of condenser 44. By reason of the magnetic coupling normally existing between the loops 39 and 40 of terminal station 1 and the normal tendency of capacity feed-back therebetween, I provide a counter feed-back system 45 including a transformer, the winding 46 of which is connected in series with the receiving loop circuit 39, and the winding 43 of which is connected in series with the transmitting loop circuit 40. The effect of the output circuit of tube 3 upon the input circuit thereof is therefore neutralized at the terminal station 1. The distant cooperative station 2 is arranged in a manner similar to the arrangement of circuits at terminal station 1. The transmitter branch of the terminal station 2 including loop 42 is tuned by means of condenser 47. For preventing the feed-back of energy locally at terminal station 2, I provide a counter feed-back system represented at 48 including one winding 49 in circuit with the receiving loop 41 and another winding 50 in circuit with the transmitting loop 42. The output circuit of one station is thus effective upon the input circuit of a distant station and vice versa, so that the system is a cooperative generator of a common carrier, and as before signaling currents can be applied for modulation of the common carrier at either or both stations, and reception or detection of the signals accomplished at each station. Here the transmission medium is the ether or space. The feed-back necessary to overcome the attenuation of the medium must be greater, just as usual radio transmission must be more powerful than wire transmission. It is clear that in both the wire and the radio applications of my invention, the feed-back couplings must be proper for cooperative generation of the carrier and not in the direction to deamplify any initial currents which will stop or start the system oscillating. If the path over the medium is identical in both directions, any shifting in phase of the feed-back will be compensated by a similar shift of phase in the feed-back in the reverse direction. In the circuits of Fig. 3, the loop system 39 cooperates with loop system 42 while loop system 40 cooperates with loop system 41.

In Fig. 4, I have shown one application

of my invention to a space radio system, wherein a different frequency is transmitted in each direction. These frequencies are cooperatively generated by the conjoint action of terminal station 1 and terminal station 2, although there is no local source of oscillations at either station of the frequency transmitted from that station. There is, at each station, a local source of oscillations for the purposes of heterodyning, the sum frequency being used at one station and the difference frequency being used at the other station for transmitting.

Station #1 includes an antenna-ground circuit 51—52 with a tuned input circuit represented at 53 having a rejector circuit 54 therein. The circuit 53 connects with the input circuit of a detector tube 55 which is acted upon by the local oscillations derived from the oscillator 56. The resultant frequency is impressed upon the amplifier circuit 57 and then upon the input circuit of a second detector 58 for operating the telephones 59. The transmitter is shown as including the microphone control circuit heretofore concerned in connection with Figs. 2 and 3, the electron tube 27, and the electron tube system 60, the output circuit of which is coupled to the antenna-ground circuit through winding 61. The oscillations of the electron tube system 60 are controlled from a winding 62 coupled between the output circuit of amplifier 57 and the input circuit of detector 58 and connected through amplifier 63 with the input circuit of tube 60. At each station, the antenna has two degrees of freedom (two resonant periods) one for transmission and one for reception, and a part of this circuit 54 excludes the frequency of the output or transmission part from the input or receiver part. As indicated at station #1, one resonant period of the antenna which forms the input circuit to the detector 55 is for an incoming wave f_1 of for example 1000 kc. and there is also associated with the input of 55, a local source 56 of oscillations f of 20 kc. The output of 55 then has in addition to the frequencies impressed upon the input also the sum and difference frequencies $f_1 + f$ and $f_1 - f$ or 1020 kc. and 980 kc. The input of tube 57 selects in this case the difference frequency 980 kc. and supplies it to two sources; to the second detector 58 for detection of signaling currents and to the power amplifiers 63 and 60 which apply it as a transmitting frequency to the antenna. The microphone 24 voice controls a modulator tube 27 to modulate the outgoing 980 kc. wave.

At station #2, a similar arrangement of circuits is provided where the antenna-ground circuit 64—65 connects to a circuit 66 wherein a rejector circuit 67 is connected. A detector 68 is provided for cooperating with the local source of oscillation 69, the result-

ant of which is impressed upon the tuned amplifier circuit 70. The output of amplifier 70 is divided and supplied through winding 71 to the power amplifier 72 and also to the tuned input circuit of the detector 73 for actuation of the telephone receivers 74. The output of the power amplifier 72 leads to the power amplifier 75 for controlling the supply of high frequency energy to the antenna-ground circuit 64—65 through coupling coil 76. At station #2 it is 980 kc. that is being received and the same frequency f of 20 kc. that is used as a heterodyne or modulator to produce in the output of 68 of station #2, the sum frequency of 1000 kc. and difference frequency of 960 kc. At this station, the input of 70 selects the sum frequency of 1000 kc. supplying it to the detector 73 and also to the power amplifier tubes 72 and 75 so at this station 1000 kc. is radiated. It will be clear from the previous figures that in order that station #1 may radiate 980 kc. and station #2 may radiate 1000 kc., the two stations must cooperatively generate and this generating will function if each station offers sufficient amplification in its circuit to overcome the attenuation of the transmission medium.

It will be understood that the circuit arrangements at stations 1 and 2 are such that while station 1 is transmitting signaling energy, at say 980 kc., which is being received at station 2, station 2 is also radiating energy, at say 1000 kc., which is being received at station 1. For the purposes of explaining my invention, I have indicated by notes on the official drawings these relative values, but it will, of course, be understood that these values are merely illustrative and are not to be taken in the limiting sense.

Various modifications of my invention will be apparent to those skilled in the art, and while I have described my invention in certain of its preferred embodiments, I desire that it be understood that no limitations are intended other than are imposed by the scope of the appended claims.

What I claim as new and desire to secure by Letters Patent of the United States is as follows:

1. In an intercommunication system, transmitting and receiving stations, means at each of said stations for cooperatively generating high frequency oscillations, and means at each station for preventing the generation of oscillations at said stations independently of the cooperative effects of said other station said last named means comprising a coupling arrangement by means of which the output and input circuit of said high frequency oscillation generating means are coupled together to suppress self excited oscillations in said oscillation generating means.

2. In an intercommunication system a pair of communicating stations, means at each of

said stations for cooperatively generating high frequency oscillations, said means having input and output circuits, and means at each station for preventing the generation of oscillations independently of the effects of the other cooperating station said last named means comprising inductance coils in the input and output circuits of said high frequency oscillation generating means said inductance coils being coupled together to suppress self excited oscillations in said oscillation generating means.

3. In an intercommunication system, comprising a plurality of stations, an electron tube system at each of said stations, said electron tube system including input and output circuits, with the output circuit of the electron tube system at one station arranged to affect the input circuit of the electron tube system at said other station for establishing oscillations by the cooperative effects of said electron tube systems and means for preventing the electron tube system at each of the stations from generating self excited oscillations, said last mentioned means comprising inductance coils in the input and output circuits of each electron tube system, coupled together in counter-feedback relation.

4. In an intercommunication system a plurality of stations, each of said stations including an electron tube system having input and output circuits, means for electrostatically and electromagnetically isolating the output circuit from the input circuit of the electron tube system of each station, and means for affecting the output circuit of the electron tube system at one station by the input circuit of the electron tube system at the other station, with the output circuit of the electron tube system at said last mentioned station connected with the input circuit of the electron tube system at said aforementioned station for the establishment of high frequency oscillations by the cooperative effects of said stations.

5. A system for generating oscillations comprising in combination a plurality of electron tube units each unit having input and output circuits, each of said units being separated from the other, an inductance in the input circuit and an inductance in the output circuit of each of said units, means for inductively coupling said input inductance and said output inductance of each unit in counter-feedback relation whereby self-excited oscillations in each of said units are suppressed, the input circuit of each unit being excited from the oscillations received from the output circuit of another unit.

6. In a communication system, a plurality of stations each adapted to transmit and receive, an electron tube system for each of said stations, input and output circuits for each of said electron tube systems, means for electrostatically and electromagnetically isolat-

ing the output circuit from the input circuit of each station, an inductance coil in each of said input and output circuits, the inductance coils at each station being inductively coupled, means for affecting the input circuit of one station by the output circuit of another station, and means at each station for generating high frequency oscillations in co-operation with another station.

In testimony whereof I affix my signature.

HAROLD M. LEWIS.
